H. W. ULRICH

TELEPHONE EXCHANGE SYSTEM

Filed Sept. 5, 1919

by *Herberto* Att'y

UNITED STATES PATENT OFFICE.

HORACE W. ULRICH, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 5, 1919. Serial No. 321,853.

To all whom it may concern:

Be it known that I, HORACE W. ULRICH, a citizen of the United States, residing at East Orange, in the county of Essex, State of New Jersey, have invented certain new and useful Improvements in Telephone-Exchange Systems, of which the following is a full, clear, concise, and exact description.

This invention relates to telephone exchange systems, and more particularly to such systems in which connections between telephone lines terminating at manual and automatic exchanges are established by way of trunk circuits, over which automatic switches are controlled from the manual exchange for effecting connections between the trunk circuits and telephone lines at the automatic exchange.

The object of this invention is the production of an improved system of this character by which the operators at a manual exchange may control over the trunk circuit the automatic switches provided at the automatic exchange, for establishing connections between the trunk circuits and the telephone lines.

In accordance with the various features of this invention, an operator's impulse sending device provided at the manual exchange and common to the link circuits thereof, is rendered individual to any one of the link circuits by the actuation of a switch individual thereto; means provided in an associated trunk circuit extending to the automatic exchange is responsive to the actuation of the switch to interrupt the continuity of the trunk circuit, and means associated with the engaged link and trunk circuits is thereafter controlled by the impulse sending device to intermittently close the trunk circuit extending to the automatic exchange for controlling the selecting mechanism thereat.

For a more complete understanding of this invention, reference should be had to the following description considered in connection with the accompanying drawing which illustrates one embodiment of the invention.

There is shown in the drawing a telephone line A, terminating at a manual exchange, where it may be connected with the link circuit B in any suitable and well known manner. The calling end of the link circuit B may be connected with the trunk circuit C

extending from the manual to an automatic exchange, at which are provided the usual selector and connector switches, for effecting connection between the trunk circuit and telephone lines, such as D, terminating at the automatic exchange. At the automatic exchange the trunk circuit is multiplied to 60 to the jack terminals at a toll switchboard at which is located the link circuit E, by means of which connection may be established with the trunk circuit and signals at the manual exchange controlled therefrom. The apparatus shown to the left of the vertical dotted line is located at the manual exchange, while that shown to the right of 70 the dotted line is located at the automatic exchange. The nature of this invention is such that it is believed a clear understanding thereof will be obtained from a description of the operation of systems shown in 75 the drawing and it will be so described.

The subscriber at the station on telephone line A having initiated a call and the answering end of the link circuit B having been associated therewith in any well known 80 manner, the operator actuates listening key 5, connecting the operator's telephone set in circuit so that the operator may converse with the calling subscriber and ascertain the number of the line with which connection 85 is desired. Assuming that connection is desired with telephone line D which terminates at the automatic exchange, the operator inserts calling plug 6, of the link circuit B, into jack 7 of the trunk circuit C. 90 Relays 8 thereupon operates over a circuit from battery through resistance 9, lower normal contact of sending device connecting key 10, sleeve contacts of the plug 6 and the jack 7 and the windings of relay 8 to ground. Relay 8 in operating opens its right-hand contact, disconnecting the energizing winding of ring-up relay 11 from bridged relation with the talking conductors of the trunk circuit C and closes its left- 95 hand contact causing the energization of relays 12, 13 and 14. The first two relays, 12 and 13, operate over a circuit from battery through the winding of relay 13, the right-hand winding of relay 12, and the left-hand contact of relay 8 to ground. Relay 12 in operating connects its low resistance left-hand winding in parallel with the high resistance right-hand winding of relay 8, while the operation of relay 13 opens a 110

contact in the circuit of relay 15 and a contact in circuit with relay 16, the former of which is connected with the tip talking conductor of the trunk circuit and the latter with 5 the ring talking conductor thereof. The operative association of these relays 15 and 16 with the talking conductors is thereby interrupted. Relay 13 also causes the operation of busy signal 17 and bridges ring- 10 response relay 18 across the talking conductors of the trunk circuit. Relay 14 operates over a circuit from battery through the contact of relay 18, winding of relay 14, and the left-hand contact of relay 8 to 15 ground. Relay 14 in operating establishes a short circuit for the right-hand winding of relay 12. This relay 12 thereupon releases its armature since, when it is in circuit with resistance 9 and its right-hand winding is 20 short-circuited, and the normal contact of listening key 5 is open, it does not receive sufficient current through its left-hand winding to hold its armature attracted. Condensers 28 and 29 connected in the talking 25 conductors of the trunk circuit C serve to electrically divide these conductors into inner and outer sections, so that current from the battery in the link circuit will not flow out to the automatic exchange and 30 current from the battery at the automatic exchange will not affect apparatus connected with the inner section of the talking conductors.

The operator after connecting the link 35 circuit B with the trunk circuit C may actuate the sending device connecting key 10, which interrupts the continuity of the tip talking conductor and sleeve conductor of the link circuit B, whereupon relays 8, 13 40 and 14 release their armatures, reconnecting relays 11, 15 and 16 with the talking conductors. The closure of the lower alternate contact of key 10 causes the operation of pilot relay 20 over a circuit from battery 45 through resistance 9, lower alternate contact of key 10, and the winding of pilot relay 20 to ground. A sending device pilot lamp 21 is thereupon lighted. The release of relay 13 causes the operation of relay 16 over 50 a circuit from battery through the winding of supervisory relay 22, lower normal contact of ringing key 23, ring contacts of the plug 6 and the jack 7, winding of relay 16, normal contact of relay 11, and right-hand 55 normal contact of relay 13 to ground. Relay 16 in operating interrupts the continuity of the tip and ring talking conductors of the outer section of the trunk circuit and opens the original operating circuit of busy signal 17, but before this operating circuit is 60 opened a holding path is established therefor so that busy signal 17 is maintained operated while relay 16 is energized.

The closure of the upper alternate contact of key 10 connects the operator's im-

pulse sending device 24 with the tip talking conductor of the engaged link and trunk circuits B and C, causing the energization of relay 15 over a circuit from battery through the outer left-hand contact of relay 13, winding of relay 15, tip contacts of the jack 7 and the plug 6, upper alternate contact of key 10 and the contact of sending device 24 to ground. Relay 15 upon being energized closes its outer right-hand contact, causing the energization of impulse-responsive relay 25 over a circuit from battery through the left-hand winding of impulse-responsive relay 25, left-hand contact of cutoff relay 34, outer right-hand contact of relay 15, upper alternate contact of relay 16, right-hand contact of cutoff relay 34, and the right-hand winding of impulse-responsive relay 25 to ground. Relay 15 is thereafter deenergized upon each opening of the contact of sending device 24 and energized upon each closure of this contact, so that impulse-responsive relay 25 follows the operation of the sending device 24 to control the usual motor magnets and other control apparatus governing the selector and connector switches at the automatic exchange.

After the requisite selecting impulses have been transmitted, due to the operation of the impulse sending device 24, the switches 26 and 27 establish connection between the trunk circuit C and the telephone line D. The operator may, after the selecting impulses have been transmitted, first restore the connecting key 10 to its normal position and then restore listening key 5 to its normal position. Upon the restoration of key 10 to normal position, the impulse sending device 24 and the pilot relay 20 are disconnected from the link circuit B and the continuity of the tip talking and sleeve conductors of the link circuit are reestablished. Upon the opening of the alternate contacts of this key 10, relays 15 and 16 deenergize and release their armatures, and upon the closure of the lower normal contact of the key, relay 8 operates causing the operation of relays 12, 13 and 14. The operation of relay 14 short-circuits the right-hand winding of relay 12, causing the deenergization of this relay 12 in the manner before described. The restoration of the listening key 5 to normal position disconnects the operator's telephone set from the link circuit and connects supervisory lamp 30 and resistance 31 in parallel with the resistance 9 and in circuit with the windings of relay 8. The lamp 30 will not be lighted while the right-hand winding of relay 8 is in circuit therewith.

The party at the station on telephone line D, in responding to the operation of the call bell thereat (the operation thereof being caused in any well known manner) removes the receiver from the switchhook

whereby the parties at the stations on the telephone lines A and D may converse. At the conclusion of the conversation the subscribers restore the receivers to the switch-
 5 hooks and the operator at the manual exchange, after observing the usual disconnect signal resulting from the restoration of the receiver to the switchhook on telephone line A, disconnects the plug 6 from the jack 7, whereupon the apparatus of the link and trunk circuits restores to normal position.
 Should the toll operator at the automatic exchange desire to establish connection with a telephone line terminating at the manual
 10 exchange, plug 35 of the link circuit E is inserted into jack 36 and ringing key 37 is actuated and restored to normal position. Cutoff relay 34 operates upon connection of the link circuit E with the trunk circuit C
 15 to disconnect the impulse-responsive relay 25 from the trunk circuit, whereby the false operation of the automatic switch control apparatus is prevented. Relay 46 also operates, causing supervisory lamp 44 to be
 20 lighted until the manual operator answers. The actuation of this ringing key causes the energization of ring-up relay 11 over a circuit from a source of ringing current 38, lower alternate contact of ringing key 37,
 25 ring contacts of the plug 35 and the jack 36, lower normal contact of relay 16, right-hand contact of relay 8, left-hand winding of relay 11, condenser 39, upper normal contact of relay 16, tip contacts of the jack 36
 30 and the plug 35, and the upper alternate contact of ringing key 37 to ground. Relay 11 upon being energized, locks up over a circuit from battery through its right-hand winding and right-hand alternate contact, and
 35 the inner right-hand contact of relay 13 to ground. The closure of the left-hand contact of relay 11 causes lamp 40 to be lighted over a circuit from battery through the left-hand contact of relay 11, left-hand normal contact of relay 15, and the lamp 40 to ground. Relay 11 in operating also opens a
 40 contact in circuit with relay 16.
 The operator at the manual exchange upon observing the lighted condition of the lamp 40, inserts plug 6 of the link circuit B into the jack 7 of the trunk circuit C. Relays 8, 12, 13 and 14 thereupon operate in the manner before described. The operation of relay 13 opens the locking circuit of relay 11
 45 which thereupon releases its armatures, extinguishing the lamp 40. The operation of relay 13 also causes the energization of supervisory relay 43 over a circuit from battery through the right-hand winding of relay 43, lower normal contact of ringing key 37, ring contacts of the plug 35 and the jack 36, impedance coil 45, outer right-hand contact of relay 13, tip contacts of the jack 36 and the plug 35, the upper normal contact of ringing key 37 and the left-hand
 50 winding of supervisory relay 43 to ground. The operation of supervisory relay 43 extinguishes the supervisory lamp 44 indicating to the toll operator that the manual operator has answered. The operation of relay 14 establishes a short circuit for the right-hand winding of relay 12 but this relay 12 does not release its armature at this time, for listening key 5 is in its normal position and the lamp 30 and resistance 31 are
 55 connected in parallel with the resistance 9. Therefore, sufficient current traverses the left-hand winding of relay 12 to cause it to maintain its armature attracted. This low resistance left-hand winding of relay 12 is connected in parallel with the high resistance right-hand winding of relay 8 so that the lamp 30 receives sufficient current to cause it to be lighted.
 The toll operator after restoring ringing key 37 to normal position and after noting that the supervisory lamp 44 has been extinguished, may actuate listening key 41 connecting the toll operator's telephone set with the talking conductors. Likewise the operator at the manual exchange after inserting the plug 6 into the jack 7, may actuate the listening key 5 to connect the manual operator's telephone set with the talking conductors so that the two operators
 60 may converse. The opening of the normal contact of listening key 5 removes the lamp 30 and the resistance 31 from parallel relation with the resistance 9, thereby increasing the resistance in circuit with the left-hand winding of relay 12. Sufficient current does not flow through this winding to cause the armature to be maintained in attracted position so that this armature is released. Of course, the opening of the normal contact of listening key 5 extinguished the lamp 30. By means of the link circuit B, the operator at the manual exchange may complete connection with the desired telephone line in the usual and well known manner. After establishing such connection the respective listening keys of the operators
 65 may be restored to normal position. The restoration of the listening key 5 to normal position reconnects the lamp 30 and resistance 31 in parallel with the resistance 9: The contact of relay 12 is at this time open and the right-hand winding thereof is short-circuited so that relay 12 is not reenergized, and since the low resistance left-hand winding of relay 12 is not connected in parallel with the high resistance right-hand winding of relay 8, the lamp 30 will not be lighted.
 Should the toll operator desire to recall the operator at the manual exchange, this may be done by actuating the ringing key 37 for a short time. During the time that this ringing key is actuated, relay 18 energizes over a circuit from the source of ringing current
 70 75 80 85 90 95 100 105 110 115 120 125 130

38, lower alternate contact of ringing key 37, ring contacts of the plug 35 and the jack 36, condenser 42, winding of relay 18, outer right-hand contact of relay 13 and outer 5 left-hand contact of relay 14 in parallel, tip contacts of the jack 36 and the plug 35, and the upper alternate contact of ringing key 37 to ground. During the energization of relay 18 the energizing circuit of relay 14 is opened at the contact of relay 18 and relay 14 releases its armatures. The opening of the inner left-hand contact of relay 14 opens the short circuit about the right-hand winding of relay 12 so that this 10 winding is included in series with the winding of relay 13 and relay 12 thereupon energizes. Upon being energized relay 12 is locked up over the circuit which includes supervisory lamp 30, normal contact of 15 listening key 5, and the left-hand winding and contact of relay 12. The left-hand winding of relay 12 is now connected in parallel with the right-hand winding of relay 8 so that the lamp 30 lights. 20 25 The deenergization of relay 18 upon the restoration of the ringing key 37 to normal position reestablishes the energizing circuit of slow-release relay 14, whereby the short circuit about the right-hand winding of relay 12 is reestablished. Relay 12 remains energized, however, since when the lamp 30 is in circuit therewith, it receives sufficient current to maintain its armature attracted. Relay 14 is made slow in releasing so that 30 the short circuit about the right-hand winding of relay 12 will not be interrupted, due to any merely momentary energization of relay 18. The outer right-hand contact of relay 13 and the outer left-hand contact of 35 relay 14 are connected in parallel so that the bridge of the talking conductors containing the relay 18 will not be interrupted should the operator at the manual exchange momentarily remove the plug 6 from the jack 7. 40 45 The operator at the manual exchange upon observing the lighted condition of the lamp 30 may actuate listening key 5 to connect the telephone set in circuit with the talking conductors so that this operator may converse with the toll operator, whose telephone set is connected in circuit therewith upon the actuation of the listening key 41. The opening of the normal contact of listening key 5, extinguishes the supervisory lamp 30 and causes relay 12 to release its armature. 50 55

What is claimed is:

1. In a telephone exchange system, in combination, a trunk circuit, an operator's link circuit connected therewith, an impulse sending device, a key for connecting the impulse sending device with the link circuit, means responsive to the connection of the impulse sending device with the link circuit for interrupting the continuity of the talking conductors of the trunk circuit, an im- 60 65

pulse responsive relay, and means responsive to the actuation of the impulse sending device for intermittently bridging the talking conductors of the trunk circuit to control the impulse responsive relay. 70

2. In a telephone exchange system, in combination, a trunk circuit comprising a pair of talking conductors, a normally open bridge for the talking conductors, an impulse responsive relay, an impulse sending device, a relay controlled over a portion of the talking conductors of the trunk circuit by the impulse sending device for intermittently closing the bridge to control the impulse responsive relay and means responsive to the disconnection of the impulse sending device from the trunk circuit for disconnecting the relay from the talking conductors. 75 80

3. In a telephone exchange system, in combination, a trunk circuit comprising a pair of talking conductors, an operator's link circuit connected with the trunk circuit, a normally open bridge for the talking conductors, an impulse responsive relay, an impulse sending device, a key for connecting the impulse sending device with the link circuit, and a relay controlled solely over a portion of one of the talking conductors of the trunk circuit by the impulse sending device for intermittently closing the bridge to control the impulse responsive relay. 85 90 95

4. In a telephone exchange system, in combination, a trunk circuit comprising a pair of talking conductors, an operator's link circuit, an impulse sending device, an impulse responsive relay, means responsive to the connection of the link circuit with the trunk circuit for close-circuiting the talking conductors, a key for connecting the impulse sending device with the link circuit, and a relay controlled solely over a portion of one of the talking conductors of the trunk circuit by the impulse sending device for intermittently interrupting the closed circuit including the talking conductors to control the impulse responsive relay. 100 105 110

5. In a telephone exchange system, in combination, a manual exchange, an automatic exchange, a trunk circuit comprising a pair of talking conductors extending between said exchanges, an operator's link circuit, means responsive to the connection of the link circuit with the trunk circuit for close-circuiting the talking conductors, an impulse sending device, a key for connecting the impulse sending device with the link circuit, an impulse responsive relay at the automatic exchange, and a relay controlled solely over a portion of one of the talking conductors by the impulse sender for intermittently interrupting the closed circuit including the talking conductors to control the impulse responsive relay. 115 120 125 130

6. In a telephone exchange system, in combination, a trunk circuit comprising a pair of talking conductors, a link circuit, a primary relay responsive to the connection 5 of the link circuit with the trunk circuit for close-circuiting the talking conductors, an impulse sending device, an impulse responsive relay, a secondary relay controlled over a portion of one of the talking conductors 10 by the impulse sending device for intermittently interrupting the closed circuit including the talking conductors to control the impulse responsive relay, and means responsive to the disconnection of the impulse sending 15 device from the link circuit for disconnecting the secondary relay from the talking conductors.
7. In a telephone exchange system, in combination, a trunk circuit comprising a pair of talking conductors, a link circuit connected with the trunk circuit, a primary relay energized over a portion of one of the engaged talking conductors of the link and 20 trunk circuits, a secondary relay energized over a portion of the other engaged talking conductor of the link and trunk circuits, means controlled by the primary and secondary relays for close-circuiting the talking conductors, an impulse responsive relay, 25 and an impulse sending device connected with the link circuit and controlling the secondary relay for intermittently interrupting the closed circuit including the talking conductors to control the impulse responsive relay.
8. In a telephone exchange system, in combination, a trunk circuit comprising a pair of talking conductors, inductive means connected in and electrically dividing the 30 talking conductors into inner and outer sections, an operator's link circuit, means responsive to the connection of the link circuit with the trunk circuit for close-circuiting the talking conductors of the outer section, an impulse sending device connected with the trunk circuit, an impulse responsive relay, and a relay controlled solely over a portion of one of the talking conductors of the inner section by the impulse sending 35 device for intermittently interrupting the closed circuit to control the impulse responsive relay.
9. In a telephone exchange system, in combination, a trunk circuit comprising a pair of talking conductors, inductive means connected in and electrically dividing the talking conductors into inner and outer sections, a link circuit, means responsive to the connection of the link circuit with the 40 trunk circuit for close-circuiting the talking conductors of the outer section, an impulse sending device connected with the link circuit, an impulse responsive relay, a relay connected with one of the talking conductors of the inner section and controlled by the 45 sending device for intermittently interrupting the closed circuit to control the impulse responsive relay, and means responsive to the disconnection of the impulse sending device from the link circuit for interrupting the operative association of the relay with the talking conductor.
10. In a telephone exchange system, in combination, a trunk circuit comprising a pair of talking conductors, inductive means connected in and electrically dividing the talking conductors into inner and outer sections, a link circuit connected with the trunk circuit, a primary relay connected with one of the talking conductors of the inner section, a secondary relay connected with the other talking conductor of the inner section and cooperating with the primary relay to close-circuit the outer section, an impulse responsive relay, and an impulse sending device connected with the line circuit and controlling the secondary relay for intermittently interrupting the closed circuit to control the impulse responsive relay.
11. In a telephone exchange system, in combination, a trunk circuit comprising a pair of talking conductors, inductive means connected in and electrically dividing the talking conductors into inner and outer sections, a link circuit connected with the trunk circuit, a primary relay connected with one of the talking conductors of the inner section, a secondary relay connected with the other talking conductor of the inner section and cooperating with the primary relay to close-circuit the outer section, an impulse responsive relay, an impulse sending device connected with the link circuit and controlling the secondary relay for intermittently interrupting the closed circuit to control the impulse responsive relay, and means responsive to the disconnection of the impulse sending device from the link circuit for interrupting the operative association of the primary and secondary relays with the talking conductors.
12. In a telephone exchange system, in combination, a trunk circuit comprising a pair of talking conductors, inductive means connected in and electrically dividing the talking conductors into inner and outer sections, a link circuit connected with the trunk circuit, a primary relay connected with one of the talking conductors of the inner section, a secondary relay connected with the other talking conductor of the inner section and cooperating with the primary relay to close-circuit the outer section, an impulse responsive relay, an impulse sending device connected with the link circuit and controlling the secondary relay for intermittently interrupting the closed circuit to control the impulse responsive relay, and a relay energized over a circuit independent of the talking conductors in response to the disconnection of the impulse sending device.

tion of the impulse sending device from the link circuit for interrupting the operative association of the primary and secondary relays with the talking conductors.

5 13. In a telephone exchange system, in combination, a trunk circuit comprising a pair of talking conductors, a cord circuit connected with the trunk circuit, a relay operating over a portion of one of the talk-

10 ing conductors of the trunk circuit and the connected cord circuit to interrupt the continuity of the talking conductors, an impulse responsive relay, an impulse sending device connected with the cord circuit, and a relay

15 connected with the other talking conductor and controlled by the impulse sending device for intermittently close-circuiting the talking conductors to control the impulse responsive relay.

20 14. In a telephone exchange system, in combination, a trunk circuit comprising a pair of talking conductors, a link circuit connected with the trunk circuit, a relay operating over a portion of one of the talk-

25 ing conductors to interrupt the continuity of the talking conductors, an impulse responsive relay, an impulse sending device connected with the link circuit, a relay con-

nected with the other talking conductor and controlled by the impulse sending device for intermittently close-circuiting the talking conductors to control the impulse responsive relay, and a relay responsive to the disconnection of the impulse sending device from the link circuit for interrupting the operative association of the primary and secondary relays with the talking conductors.

30 15. In a telephone exchange system, in combination, a trunk circuit comprising a pair of talking conductors, inductive means connected in and electrically dividing the talking conductors into inner and outer sections, an impulse responsive relay, an impulse sending device, a cord circuit having a key therein for connecting the impulse sending device with the trunk circuit, and a relay controlled solely by the impulse sending device over one of the talking conductors of the inner section for intermittently close-circuiting the outer section to control the impulse responsive relay.

35 40 45 In witness whereof, I hereunto subscribe my name this 2nd day of September A. D., 1919.

HORACE W. ULRICH.
